CARPET SWEEPER

Frank Robinson and Charles Idenden Betts,
Maidstone, EnglandApplication March 5, 1934, Serial No. 714,139
In Great Britain June 8, 1933

4 Claims. (Cl. 15—41)

This invention relates to carpet sweepers of the type provided with floor or track wheels which also operate to effect the driving of a rotary brush comprised in the sweeper by frictional contact 5 with rollers provided at the ends of the brush spindle.

In carpet sweepers of this type heretofore known the floor or track wheels have been respectively mounted on the ends of straight rods 10 passing entirely across the space within the casing, the wheels being supported on the ends of the rods outside the casing. The rods pass through slots or enlarged openings in the sides of the casing and are urged towards the ends of the 15 slots or sides of the holes by springs which also act to press the track wheels into contact with the rollers on the brush spindles.

According to this invention, in order to obviate the disadvantage of the known arrangement of 20 the wheel supporting rods wherein they pass across the space close to the dust receiving pans into which dust is thrown by the brush, the said rods are bent or cranked at parts thereof within the casing so as to avoid causing obstruction of 25 the space across which dust is thrown from the brush into the said pans.

In the accompanying drawing:

Figure 1 shows a side view in vertical section transverse to the brush spindle and wheel supporting rods, of a carpet sweeper in accordance 30 with this invention.

Figure 2 shows a part of the carpet sweeper in section on the line x—x, Figure 1.

As shown in this drawing, the ends 1 of rods or 35 wires which support floor or track wheels 2 pass through holes 3 of larger diameter formed in the sides 4 of the casing and each rod or wire intermediate of the parts extending through the holes or slots 3, is bent to provide parts 1a lying close 40 to the sides of the casing on the inside thereof and a part 1b extending across the casing from side to side close to the top or cover 4a of the casing. Thus the parts of the rods within the casing occupy positions close to the inside walls 45 thereof, allowing larger or deeper dust collecting pans to be used. A similar result can be attained by arranging the parts 1b, for example, near to the end walls 4b.

The parts 1b of each rod or wire are supported 50 by springs 5 or resilient arms, one adjacent to each side of the casing, and the ends 1 of the rods or wires at each side of the casing are urged one towards the other by a spring 6 to press the wheels 2 against a roller 7 on the brush spindle 55 8 which is rotatably supported at opposite ends as usual by pins 9 on a band 10 secured around

the outside of the casing, the said pins extending into axial holes in the spindle 8.

A bar 11 secured to a block 12 provided for carrying a comb 13 for cleaning the brush, or otherwise mounted within the casing, is optionally provided near each end of the part 1b to limit downward movement of the rod or wire. Thus the movements of the parts 1b are confined within limits whilst allowing sufficient movement thereof as required when the ends 1 of the rods 10 or wires move to different positions in the slots or holes 3 by reason of variable yielding of the springs 5, 6 under variations of the load imposed thereon by or through the casing.

We claim:

1. In a carpet sweeper comprising a casing, a rod having an intermediate part thereof extending across the casing from side to side near the top thereof, resilient arms supporting the said intermediate part, terminal parts of the said rod 20 extending outside the casing out of alignment with the intermediate part, and track wheels mounted on the ends of said rods.

2. In a carpet sweeper comprising a casing, a rod having an intermediate part thereof extending across the casing from side to side near the top thereof, parts extending close to the lateral walls of the casing, parts extending outside the casing, track wheels mounted on the parts of the rod outside the casing, resilient arms supporting the said intermediate part, and a bar for limiting the movement of the intermediate part of the said rod.

3. In a carpet sweeper comprising a casing, a rod having the ends thereof extending through holes of larger diameter than the rod formed in the lateral walls of the said casing, a part of the said rod extending close to the said lateral walls, an intermediate part of the rod extending across the casing near to the top thereof, a second rod 40 arranged similarly to the above mentioned rod, springs for urging the ends of one rod towards the ends of the other rod, and track wheels mounted on the said rods exterior to the casing.

4. In a carpet sweeper comprising a casing, a rod having the ends thereof extending through holes of larger diameter than the rod formed in the lateral walls of the said casing, a part of the said rod extending close to the said lateral walls, an intermediate part of the rod extending across the casing near to the top thereof, resilient arms supporting the said intermediate part, and track wheels mounted on the ends of the said rod exterior to the casing.

FRANK ROBINSON.
CHARLES IDENDEN BETTS.
